UNITED STATES PATENT OFFICE.

AARON C. HINES, OF TUCUMCARI, NEW MEXICO.

FOLDING WASHBENCH.

Application filed December 1, 1922. Serial No. 604,363.

To all whom it may concern:

Be it known that I, AARON C. HINES, a citizen of the United States, residing at Tucumcari, in the county of Quay and State 5 of New Mexico, have invented certain new and useful Improvements in Folding Washbenches, of which the following is a specification.

My invention relates to a bench or stand 10 for wash tubs and the main object is to provide a portable bench which, may be folded, when not in use, to be stored away, thus occupying a very small space.

Another object of the invention is to provide room for two, three or more tubs on 15 the bench and if constructed for three wash tubs, for instance, it may still be set up for only two, of them, when the support or extension for the third wash tub is folded and 20 therefore takes up very little room. In this manner the bench is adjustable in accordance to the number of tubs to be used at one time.

One embodiment of the invention is ill- 25 lustrated in the accompanying drawings, and

Figure 1 shows a perspective view of the wash bench erected for use to hold three wash tubs;

Figure 2 is perspective view of the bench 30 folded for storing;

Figure 3 is a top plan view of the bench unfolded;

Figure 4 is a fragmentary elevation indicating the manner of attaching supporting 35 legs to the bench, and

Figure 5 indicates a hinge connection for the extension or auxiliary frame adapted to carry a third wash tub.

The bench consists of a main frame 10 40 preferably constructed of wooden beams 11 to form longitudinal side runners thereof. It is evident that structural iron may be used for these beams. The beams 11 are spaced apart and in parallel relation and are rigidly connected by means of central slats 12 and end slats 13, the latter being placed at the extreme ends of the beams 11 and all the slats secured in any suitable manner, as by bolts, screws, nails or 45 rivets. The slats may be made of hard wood or band iron and are placed a suitable distance apart for conveniently supporting the wash tubs.

At the right hand ends of the beams or 50 runners 11 are secured brackets 14 to the outer sides thereof and the brackets extend

below the bottom face of the runners and are provided with apertures for receiving a hinge rod 15, as best seen in Figures 1 and 4. Upon these rods 15 is hinged a pair of 60 supporting legs 16 at the ends of the rod 15 and connected by means of slats 17.

At the opposite end of the frame are provided other supporting legs 18 of similar construction to the ones just described and 65 secured by means of the hinge rod 15 in brackets 19, which however are placed some distance in from the extreme left hand end of the frame, as seen in Figures 1 and 2. This is for a reason that will be explained 70 further on.

Each of the supporting legs 16 and 18 is connected to the frame by means of a brace 20 hinged in the middle and fulcrumed to the inner side of each beam or runner 11, 75 as at 21 and to each leg, as at 22. These braces have the usual locking fingers indicated by reference numeral 23 adjacent the central hinge, for the purpose of preventing the folding of the braces inwardly in the direction of the brackets 14 and 19.

An auxiliary frame 24 is attached to one side and near one end of the main frame 10 by means of a pair of hinges 25, one leaf 36 of each hinge being secured to the side of one of the beams or runners 11, the other leaf 34 being secured to the top of the runner 26 in open position, as seen in Figures 1 and 5 of the drawings. The auxiliary frame also consists of a pair of 80 wooden or metal beams or side runners 26 connected by means of an inner slat 27 and an outer one 28, the latter being secured at the extreme outer ends of the runners 26, as seen in Figures 1 and 3 of the drawings and 85 in similar manner as already described in connection with the main frame 10. A pair of supporting legs 29 of similar construction as the supporting legs 16 and 18 is carried on a hinge rod 30 mounted in the brackets 100 31 secured to the outer sides in adjacent ends of the runners or beams 26. The supporting legs 29 are also provided with upper connecting slats 32 and lower connecting slats 33 and also with hinged braces 34 similar 105 to those already described. All these locking braces 20 and 34 run diagonally across the corners formed between the supporting legs and the respective beams or runners, when the stand or bench is erected, as best 110 seen in Figure 1 of the drawings.

The length of the auxiliary frame 24 as

well as the main frame 10 and the relative positions of the slats 12, 13, 27, and 28 is such, that the slats will give ample support for three wash tubs without crowding, the main frame being intended for two wash tubs 35, while the auxiliary frame is intended for only one.

As seen in the drawings, the width across the supporting legs 16, 18, and 29 is identical with the width of the main and auxiliary frames, so that, when the supporting legs are folded beneath the respective frames, they will occupy the same space across as the frames themselves. The width of the auxiliary frame 24 is however slightly less than the distance between the slats 12 and 13, so that when the auxiliary frame is folded over the main frame, the former will swing down between the side slats to be supported by the two runners 11 forming part of the main frame 10; while the slat 27 of the auxiliary frame drops down between the side slats and side beams. This is best seen in Figure 2 of the drawings. It will also be understood from this figure, that for only two wash tubs, the auxiliary frame may remain in folded position, one wash tub then resting on the slats 12 and 13 at the right hand end of the frame, as seen in this figure and Figure 1, while the other wash tub will stand on slats 32 and 33 connecting the supporting legs 29 of the auxiliary frame 24.

In order to store away the bench the auxiliary frame 24 is first folded over the top of the main frame with the runners 26 resting on both main runners 11 and then the braces 34 are swung downwardly, permitting the supporting legs 29 to swing down upon the beams 26 of the auxiliary frame. The bench is then stood on end and the braces 20 folded in similar manner permitting the supporting legs 16 to fold down along the main frame and the braces 20 of the other supporting legs 18 to be folded in a similar manner, also permitting the swinging of the legs 18 to lie along the under side of the runners 11. When folded flat in this manner the bench will take up very little space, so that it may conveniently be stowed away in a closet or wardrobe.

The reason for placing the supporting legs 18 further in from the end of the frame than the supporting legs 16, is to make room for the auxiliary frame 24, so that the latter may be attached as close as possible to one end of the main frame, and it is also evident that with the supporting legs 18 in this position they will furnish a firmer support for the auxiliary frame when in use.

As already stated the entire structure may be made of pine or other wood, or it may be made entirely of iron, or it may be con-

structed of part iron and part wood, depending on which material can be best obtained in the locality where the benches are built.

Having thus described the invention, what is claimed as new is:

1. A bench for wash tubs comprising a main frame, end supports for the frame and hinged braces between the main frame and the supports permitting the folding of the latter under the main frame, an auxiliary frame having hinged connection with the upper side of the main frame, a hinged support at the end of the auxiliary frame and folding braces between the auxiliary frame and the hinged support, said frames including side runners and slats connecting said runners, holding the latter in parallel spaced relation, said slats being spaced to form a base for a tub and permitting the housing of the auxiliary frame between them when said auxiliary frame is folded over the top of the main frame.

2. A bench for wash tubs comprising a main frame, end supports for the frame and hinged braces between the main frame and the supports permitting the folding of the latter under the main frame, an auxiliary frame having hinged connection with the upper side of the main frame, a hinged support at the end of the auxiliary frame and folding braces between the auxiliary frame and the hinged support, said frames including side runners and slats connecting said runners, holding the latter in parallel spaced relation, said slats being spaced to form a base for a tub and permitting the housing of the auxiliary frame between them when said auxiliary frame is folded over the top of the main frame, brackets at the ends of said frames, said supports each including a pair of legs, and suitable cross connections for said legs, the width across the legs being substantially identical with that of the respective frames.

3. A bench for wash tubs comprising a main frame and an auxiliary frame; each of said frames including side runners and slats connecting said runners and holding the latter in spaced parallel relation, said auxiliary frame having hinged connection with one of the runners of said main frame and adjacent one end thereof; end supports for each of said frames and hinged braces between said supports and the respective frames, permitting the folding of the supports under the frames, the spacing of the slats on said main frame being such that the auxiliary frame will fold between them over the top of the main frame.

In testimony whereof I affix my signature.

AARON C. HINES. [L.S.]
